UNITED STATES PATENT OFFICE.

JOSEPH CHARLES BEAUMONT, OF DUNCAN'S STATION, CANADA, ASSIGNOR
OF ONE-HALF TO ROBERT E. O'NEAL, OF SAME PLACE.

DESIGN FOR A KNEADING-BOARD.

SPECIFICATION forming part of Design No. 34,669, dated June 18, 1901.

Application filed February 26, 1901. Serial No. 49,012. Term of patent 7 years.

To all whom it may concern:

Be it known that I, JOSEPH CHARLES BEAUMONT, a subject of the King of Great Britain, residing at Duncan's Station, Vancouver Island, and Province of British Columbia, Canada, have invented and produced a certain new and original Design for Kneading-Boards; and I do declare the following to be a full, clear, and exact description of the invention, such as will enable others skilled in the art to which it appertains to make and use the same.

The invention relates to a new and original design for a kneading-board; and it consists of a design of the configuration shown in the accompanying drawings, in which—

Figure 1 is a perspective view, and Fig. 2 is a vertical sectional view.

The leading feature of the design consists of a thin rectangular body portion 1, having a flange 3 projecting upwardly at its rear end

and flanges 2 projecting upwardly from the sides of the board and leading from the ends of the flange 3 and decreasing in height from one end of the board to the other and having 25 located at their inner ends, parallel with the inner end of the board and flush with its upper surface, a longitudinally-disposed trough semicircular in vertical cross-section and provided midway its ends with an aperture, from 30 which extends downwardly a cylindrical body 5, having a bottom 6.

What I claim is—

The design for a kneading-board, as herein shown and described.

In testimony whereof I have hereunto set my hand in presence of two subscribing witnesses.

JOSEPH CHARLES BEAUMONT.

Witnesses:

ALBERT BEAUMONT,
GEO. LEWIS.
